US00D606929S

(12) **United States Design Patent**
Song

(10) **Patent No.:** US D606,929 S
(45) **Date of Patent:** ** Dec. 29, 2009

(54) **TIRE**

(75) Inventor: **Wenguang Song**, Dongying (CN)

(73) Assignee: **Xingyuan Tyre Group Co., Ltd.**,
Dongying (CN)

(**) Term: **14 Years**

(21) Appl. No.: **29/283,313**

(22) Filed: **Aug. 10, 2007**

(30) **Foreign Application Priority Data**

Jun. 19, 2007 (CN) 2007 3 0158986

(51) **LOC (9) Cl.** **12-15**

(52) **U.S. Cl.** **D12/579**

(58) **Field of Classification Search** D12/500-502,
D12/533, 539, 543, 544, 548, 551, 552, 554,
D12/557-559, 563, 564, 566, 568, 574, 578,
D12/579, 582, 583, 586, 587, 589, 592-594,
D12/599, 600, 602, 901; D21/563, 779;
152/209.1, 209.3, 209.12-209.15, 209.25,
152/209.28

See application file for complete search history.
